(57) **CLAIM**

The ornamental design for a mobile phone cover, as shown and described.

DESCRIPTION

FIG. 1 is a front, right and top perspective view of a mobile phone cover, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and

FIG. 9 is a front, left, and bottom perspective view thereof showing the front of the mobile phone cover in an alternate configuration;

FIG. 10 is a front, right, and top perspective view thereof showing the front of the mobile phone in the alternate configuration;

FIG. 11 is a perspective view thereof showing the mobile phone cover in a second alternate configuration with the selfie stick in a fully extended state; and,

FIG. 12 is another perspective view thereof showing the mobile phone cover in the second alternate configuration with the selfie stick in the fully extended state.

The broken lines shown in the drawings illustrate portions of the mobile phone cover that form no part of the claimed design.

1 Claim, 12 Drawing Sheets
